COMBINED HANDLE AND LOCK

Edwin North, Rockford, Ill., assignor to National Lock Co., Rockford, Ill., a corporation of Illinois

Application February 20, 1935, Serial No. 7,384

7 Claims. (Cl. 70—29)

This invention relates to certain novel improvements in a combined handle and lock and particularly constitutes an improvement over that shown in my companion applications Serial 5 No. 7,383 and Serial No. 7,382 filed February 20, 1935 for Letters Patent of the United States on a combined handle and lock.

The present invention has for its principal object the provision of an improved construction of 10 this character which will be highly efficient in use and economical in manufacture and in which there is embodied mechanism which is key operated to permit the elevation of a latch plate or bar lift of a door or the like.

15 Other objects will appear hereinafter.

The invention consists in the novel combination and arrangement of parts to be hereinafter described and claimed.

The invention will best be understood by reference to the accompanying drawings, showing the preferred form of construction and in which:

Fig. 1 is a face view of my combined handle and lock;

Fig. 2 is a side elevational view of the same;

25 Fig. 3 is an enlarged sectional fragmentary detail view of the same taken approximately on line 3—3 of Fig. 1;

Fig. 4 is a sectional detail view of the same taken substantially on line 4—4 of Fig. 3;

30 Fig. 5 is a sectional detail view of the same, similar to that shown in Fig. 4 showing the parts thereon in different relationship;

Fig. 6 is a sectional detail view similar to that shown in Fig. 5 with certain parts illustrated in 35 different relationship with respect to each other; and

Fig. 7 is a sectional detail view of the same taken substantially on line 7—7 of Fig. 4.

Referring more particularly to the drawings in 40 which the preferred form of construction of the invention is illustrated, a handle is indicated at 10 and this handle is provided at one end portion with a body portion providing a housing or enclosure 11 within which the lock mechanism is 45 adapted to be confined. The ends of the handle terminate into laterally extended portions or ears 12 perforated as at 13 for the projection of head-bearing connecting elements 14 which facilitate connecting the handle to a door with which it is 50 intended to be associated.

The housing includes a closure plate 15. Slidably mounted within the housing or enclosure 11 and parallel with respect to the plate 15 is a lift 16, the lower end of which provides a lateral extended finger portion 17 to facilitate engagement

therewith by the index finger of the hand when the hand of the operator grasps the handle 10.

This lift is provided at this lower end portion with a laterally extending pin 18 which is adapted to project through an opening 19 of a latch plate 5 or bar 20.

Within this housing 11 is mounted the mechanism for controlling operation of this lift 16 and in this instance this mechanism preferably includes a key guide 21 rotatably supported by the 10 housing 11 and the plate 15 as best shown in Fig. 3.

Extending laterally from the plate 15 in spaced relation with respect to each other are pins 22 which are received by slots 23 formed in the opposite end portions of an operating plate 24 15 adapted to be moved transversely of the pins within the housing 11 by the action of the key 26.

Pivotedly supported by one of the pins 22, as at 21, are a plurality of lever tumblers 28 each of which includes a slot 29 for the reception, under 20 proper conditions, of the opposite pin of the pins 22, as at 30. On opposite longitudinal sides of the slot 29 there are provided teeth-like stepped portions 31 adapted to engage the lateral stud 32 carried by and movable with the plate 24. These 25 lever tumblers are normally retained in locked relation with respect to the studs 32 by the action of a spring 33, the operation of these lever tumblers being hereinafter more fully described.

The plate 24 provides a depending portion 34 30 having a laterally extending locking finger 35 normally disposed by the action of a spring 36 in the path of movement of a fin or web 37 provided by the lift 16.

In the lift 16 there is formed an elongated slot 35 38 and projected through this slot 38 is a pin 39 pivotally supporting a spring urged latch lever 40 having a latch head 41 adapted to have latched engagement with the locking finger 35 whereby to retain the plate 24 in a position from locked 40 engagement with respect to the web 37.

As will be noted in Fig. 5, when the latching lever 40 is operable upon the locking finger 35 to retain the same from locked position with respect to the web 37, this latching lever is disposed 45 in the path of movement of the web 37; consequently, at a predetermined time the web 37 will operate upon the latching lever 40 to release the plate 24 for movement by action of the spring 36 into locking position with respect to the web 37. 50

Normally the lever tumblers are disposed out of alignment with respect to each other and are brought into proper alignment with respect to each other only upon the insertion of a proper key in the key guide 21.

When a proper key is inserted in the key guide 21 and the lever tumblers are brought into proper alignment with respect to each other, the slots 29 thereof will be disposed to receive the fingers 32 whereby to permit the plate 24 by action of rotation of the key 26 to be moved transversely of the pins 22 into a position to dispose the locking finger 35 from locking position with respect to the web 37 thereby to permit the lift 16 by the action of 10 the hand of the operator to be moved to release the latch member 20 from a latching position.

When the plate 24 has been moved into its extreme position (into the position in which it is shown in Fig. 5) from locking position with respect to the web 27, the same is held in that position against the action of the spring 36 by the latching lever 40. Such lever 40 continues to perform that function until disengaged from latched engagement with the finger 35 by a slight upward 20 movement of the handle 10 and web 37 at which time the locking finger 35 is free to move by the action of the spring 36 into locking relation with respect to the web 37 when the lift 16 is permitted to move to its original position (as in Fig. 25 4), whereupon the key 26 may be returned to its initial position (as in Fig. 4) and removed from the lock cylinder 21.

The arrangement obviously provides automatic locking of the lift.

30 It is apparent that the locking mechanism while being highly efficient in use comprises comparatively few parts.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such 40 variations and modifications as come within the scope of the appended claims.

Having thus described my invention what I claim as new and desire to protect by Letters Patent is:

45 1. A device of the class described including a handle having a latch lift associated therewith, lock mechanism including pivotally supported lever tumblers associated with the handle and including a slidably supported locking member 50 for the lift, and means for latching the locking member from locking position with respect to the lift, said latching means being disposed in the path of movement of the lift and operable by the lift to release the locking member for movement into locking position with respect to the lift.

55 2. A device of the class described including a handle having a latch lift associated therewith with the lift providing a web, lock mechanism including pivotally supported lever tumblers associated with the handle and including a slidably supported locking member for the lift, and means for latching the locking member from locking position with respect to the lift, said latching means being disposed in the path of movement of the web of 60 the lift and operable by the lift to release the locking member for movement into locking position with respect to the lift.

65 3. Locking mechanism including a handle providing a housing, a lift slidably associated with 70 the housing, a plate slidably arranged within the housing and including a locking finger dis-

posed in the path of movement of the lift, key actuated pivotally supported lever tumblers for controlling key movement of the locking finger, a latch member pivotally supported within the housing and adapted to engage the locking finger when disposed from locking position with respect to the lift, said latch member when disposed to retain the locking finger from locked position with respect to the lift being disposed in the path of and operable by the lift to release the locking finger for movement into locking position with respect to the lift. 10

4. Lock mechanism including an enclosing structure, a latch lift slidably associated with the structure, a plate slidably associated with the structure and including a locking finger adapted to lock the lift against movement, key actuated pivotally supported lever tumblers for controlling key movement of the locking finger, a structure including an operating pin, the said plate being provided with a shoulder adapted for operative engagement with the pin whereby to be moved for operative engagement with the pin whereby to be moved from locking position with respect to the lift by operation of the lock mechanism, and means operable by the lift for releasably holding the locking member from locking engagement with respect to the lift. 25

5. Lock mechanism including an enclosing structure, a latch lift slidably associated with the structure and including a web, a plate slidably associated with the structure and including a locking finger adapted to lock the lift against movement, a lock structure including key actuated pivotally supported lever tumblers and an operating pin, the said plate being provided with a shoulder adapted for operative engagement with the pin whereby to be moved from locking position with respect to the lift by operation of the lock mechanism, and means operable by the web of the lift for releasably holding the locking member from locking engagement with respect to the lift. 30

6. Lock mechanism including an enclosing structure, a latch lift slidably associated with the structure, a plate slidably associated with the structure and including a locking finger adapted to lock the lift against movement, a lock structure, key actuated pivotally supported lever tumblers and including an operating pin, the said plate being provided with means adapted for operative engagement with the pin whereby to be moved from locking position with respect to the lift by operation of the lock mechanism, and means operable by the lift for releasably holding the locking member from locking engagement with respect to the lift. 35

7. Lock mechanism including an enclosing structure, a latch lift slidably associated with the structure, a plate slidably associated with the structure and including a locking finger adapted to lock the lift against movement, a lock structure, key actuated pivotally supported lever tumblers and including an operating pin, the said plate being provided with a recessed portion adapted for operative engagement with the pin whereby to be moved from locking position with respect to the lift by operation of the lock mechanism, and means operable by the lift for releasably holding the locking member from locking engagement with respect to the lift. 40

EDWIN NORTH.
